ABSTRACT OF THE DISCLOSURE

Apparatus for replacing a supporting core of a core-supported wound package of yarn with a longitudinally compressible replacement core, in order to prepare the package of yarn for subsequent treatment such as a dyeing process or the like.

This application is a continuation-in-part of copending application Ser. No. 645,645, filed June 13, 1967.

At a certain stage in some processes for the manufacture of textile goods, yarn which is subsequently to be formed into the goods by knitting, weaving or the like is wound into packages about supporting cores and thereafter heat treated with steam or by the circulation of a hot liquid through the packages to dye or otherwise treat the yarn. In many such fluid treatment processes involving wound packages of yarn, it is preferred that the supporting core for the package during the treatment process be a perforate core, in order that fluid may flow radially of the wound package and treat the yarn uniformly throughout the package, and additionally be a longitudinally compressible core, in order that the yarn package may be compressed to occupy a smaller volume during the treatment. These two requirements that a treatment core be perforate and be longitudinally compressible have heretofore presented difficulties which have had unfavorable effects on the operations of yarn processors.

More particularly, it has heretofore been proposed that a yarn processor may avoid both the necessity of supplying a large number of relatively expensive treatment cores and the alternative necessity of processing yarn through an additional and otherwise unnecessary winding operation by the use of an apparatus and method for expelling a conventional inexpensive winding core made of rigid paper tube at the same time that a treatment core is pressed into a core supported package of yarn. However, such insertion of a replacement core and expulsion of a winding core has been most readily obtained when the replacement core is longitudinally rigid, and may be used as a force transmitting member to push the winding core from the package.

With the foregoing particularly in mind, it is an object of the present invention to provide an apparatus which avoids the deficiencies heretofore present in textile operations wherein wound packages of yarn are prepared for subsequent treatment such as dyeing by the replacement of a winding core with a longitudinally compressible treatment core. In realizing this object of the present invention, apparatus is provided for readily expelling a winding core from within a radially compressive wound package of yarn and for protecting a longitudinally compressible replacement core from gripping engagement by the package during the insertion thereof into the package. Through the employment of an apparatus as disclosed and claimed herein, a textile yarn processing operation may avoid both the necessity of providing an excessively large number of longitudinally compressible

2

replacement cores and the necessity of introducing a winding process merely to transfer yarn from one core to another. Thus, substantial economies are realized through the present invention.

Some of the objects of the invention having been stated, other objects will appear as the description proceeds, when taken in connection with the accompanying drawings, in which:

FIG. 1 is a plan view of a first type of apparatus incorporating the improvement of the present invention;

FIG. 2 is an enlarged elevation view of the apparatus of FIG. 1, taken generally along the line 2—2 in that figure;

FIG. 3 is a further enlarged view generally similar to FIG. 2, illustrating somewhat schematically one stage in the replacement of a package core by operation of the apparatus of FIG. 1;

FIGS. 4, 5 and 6 are views similar to FIG. 3 illustrating further stages in the replacement of a package core by operation of the apparatus of FIG. 1;

FIG. 7 is a side elevation view, in partial section, through a portion of the apparatus of FIGS. 3 through 6, taken generally along the line 7—7 in FIG. 5;

FIG. 8 is an elevation view of a second type of apparatus incorporating the improvement of the present invention;

FIG. 9 is an enlarged somewhat schematic elevation view of portions of the apparatus of FIG. 8, illustrating one stage in the replacement of a package core by operation of that apparatus;

FIGS. 10 and 12 are views similar to FIG. 9 illustrating further stages in the replacement of a package core by operation of the apparatus of FIG. 8;

FIG. 11 is an enlarged elevation view, in partial section, of a portion of the apparatus of FIG. 10, taken generally along the line 11—11 in that figure;

FIG. 13 is a view similar to FIG. 11, taken generally along the line 13—13 in FIG. 12; and

FIG. 14 is a plan view, in partial section, through the apparatus of FIG. 13, taken generally along line 14—14 in that figure.

Referring now more particularly to the drawings, the improvement of the present invention is there disclosed in conjunction with an apparatus including sequentially actuated operating instrumentalities as disclosed in the aforementioned patent application Ser. No. 645,645, filed June 13, 1967, and in a form suitable for semi-automatic or hand use. This discussion will proceed first with reference to the sequentially actuated apparatus, and attention is directed to the aforementioned copending patent application for a full and detailed disclosure of certain control functions and operations by which sequential advancement of wound packages of yarn to and beyond a core replacement station is coordinated with reciprocal movement of a mandrel between a position remote from the common path of the yarn packages past the core replacement station and a position at which the mandrel intersects the common path of package travel.

SEQUENTIALLY ACTUATED APPARATUS OPERATING INSTRUMENTALITIES

In order to provide for receiving a plurality of packages of yarn and for moving the packages along a predetermined common path of travel and past a core replacement station, the sequentially actuated apparatus according to the present invention provides means including upper and lower package troughs and a rotatably supported package advancing means. The package troughs include an upper package trough 50, supported on and movable with a movable frame including members 37 and 38, and a lower package trough 51, supported on a stationary frame including members 21—23 and 28—31.

Means are provided for defining a pocket at the lower end of the trough 50, and the width of the floor 54 of the trough 50 and the vertical extent of the sidewalls 55 and 56 thereof are such that packages P of yarn are received in the upper trough 50 in a predetermined common orientation, with the supporting cores thereof, hereinafter referred to as winding cores W, in a horizontal disposition, and are advanced by gravity along a predetermined common path of travel to a dispensing position in the pocket. When a package P reaches the dispensing location at the pocket, it is in position to be received by a package advancing means and to be advanced thereby in continued movement along the predetermined path.

In order to controllably advance individual packages from the package dispensing location at the extremity of the upper trough 50 along the common path of travel and past a core replacement station, this invention provides package advancing means including a rotatable member 60, formed, supported and driven in rotation all as described in the aforementioned copending application. Further, rotation of the member 60 is controlled in such a manner as to positively locate a package advanced thereby in a predetermined alignment at a core replacement station, for facilitating the replacement of a supporting core such as the winding core W as hereinafter described.

The importance of the positive location of a package P at a core replacement station, as for example by controlling the rotation of the rotatable member 60, is clear in view of the provision of a core replacing means functioning to expel a winding core W from within a package P while inserting a replacement core R thereinto. In accordance with the present invention, the core replacing means includes an elongate hollow mandrel 95 (FIG. 2) mounted on one terminal extremity of a piston rod 96 of a core replacement cylinder 97 and supported for movement along a predetermined path transverse to the common path of travel to the packages P. The predetermined path of travel for the mandrel member 95 extends between two extreme positions, one of which is remote from the core replacement station at the intersection of the mandrel path with the common path of travel of the packages P (FIG. 2) and the other of which positions the mandrel member 95 penetrating a package P (FIG. 5) at the core replacement station. Movement of the mandrel member 95 between the two extreme positions results from the application of fluid pressure to the core replacing cylinder 97, which is supported on the stationary frame with the mandrel member 95 aligned for intersection of the package path as described above.

In order to obtain the expulsion of a winding core W and the insertion of a replacement core R as described hereinafter, it is important that the hollow mandrel 95 have certain dimensional relationships to the package P and the cores W and R. In particular, the mandrel 95 must have a longitudinal dimension at least sufficient to penetrate entirely through a package P when the package is in a longitudinally compressed condition (FIG. 5). The diametrical dimensions and wall thickness of the mandrel 95 must be such that the external diameter of the mandrel is substantially equal to and not substantially greater than that of the winding core W to be expelled and that the internal diameter of the mandrel is greater than the external diameter of the replacement core R to be inserted. These diametrical relationships are necessary in order that the hollow mandrel may encircle and shield a replacement core while engaging a winding core and expelling it from a package during penetration of the mandrel into the package to serve as an intermediate supporting core during the core replacement action, as brought out by further discussion hereinafter.

In movement of the mandrel 95 from the position remote from the core replacement station along the predetermined path of mandrel travel toward the position

intersecting the paths of package travel, an open, package penetrating end of the mandrel first engages a replacement core R, and the mandrel receives the core into a cylindrical volume defined therewithin (FIG. 3). The present improvement contemplates that the replacement core R is a longitudinally compressible core made, for example only, of stainless steel wire wound into a spring form such as that disclosed in U.S. Pat. No. 2,614,764 to Annicq. With such a longitudinally compressible core, the dimensional relationships of the mandrel 95 as described above are such that the mandrel encloses the replacement core R and the leading end of the mandrel engages the trailing end of the winding core W to push the winding core from the package as the mandrel is displaced from the remote position toward the intersecting position. On enclosure of the replacement core R within the mandrel 95, the interior end of the core engages an abutment member 103 disposed within the mandrel at a predetermined distance from the open leading end thereof which is less than the normal free length of the core. Thereafter, as the leading end engages the winding core W, the replacement core R is compressed until it is entirely shielded by the mandrel (FIG. 4).

In order to provide for longitudinal compression of the package P during core replacement, a shoulder portion 98 is positioned adjacent the remote extremity of the mandrel 95, and is of sufficiently large diameter to engage a movable side plate 105, as described more fully hereinafter. Supported from adjacent the shoulder portion 98 and extending forwardly of the mandrel 95 is positioned an alignment member 96a, at least partially enclosed by the mandrel 95 and being spaced therefrom. The external diameter of the alignment member 96a is related to the internal diameter of the replacement core R in such a manner that a replacement core is received in the annular space between the mandrel and the alignment member with a very slight frictional snugness for reasons pointed out more fully hereinafter.

In order to assure accommodation of a limited range of sizes for the package P the alignment member 96a includes, at the forward extremity thereof, a tapered portion 99 faced with low friction material which, on entrance into a winding core W, raises the package P undergoing core replacement a predetermined distance, such as one inch, from the pocket of the rotatable member 60. Upon advancement of the mandrel 95 so that the tapered portion 99 of the alignment member penetrates a replacement core R and the replacement core is received within the annular volume between the alignment member 96a and the mandrel 95, the tapered portion 99 then enters the winding core W of the package and the package is displaced laterally into engagement with a fixed side plate 100, which may be faced with low friction material and have secured thereto a centering spring 101. With firm lateral support for the package P, further extension of the mandrel 95 causes the tapered portion 99 to lift the package P onto the main body of the alignment member (FIG. 3), pushes the leading end of the mandrel 95 (also referred to as the package penetrating end) into engagement with the winding core W and expels the winding core W from within the package as the replacement core R is inserted thereinto. During the insertion of the replacement core R into the package, the core is shielded from engagement by the package by the mandrel 95 and is compressed longitudinally to a predetermined length less than its normal free length between the trailing end of the core W being expelled and the abutment member 103 interposed between the mandrel 95 and the alignment member 96a (FIG. 4).

In order to break the package P by compressing the same longitudinally, and thereby assure more uniform density of the package, the apparatus is provided with a movable side plate 105, which is supported by a pair of spaced bearing rods 106 and 107 which extend through a spaced pair of supporting plate members 108 and 109 to

be guided thereby in linear movement and may have a low friction face. The movable side plate 105 is biased to a normally withdrawn position by a pair of biasing springs 110 and 111 encircling the supporting rods 106 and 107 (FIG. 2) and may carry a second centering spring 112 similar to the spring 101. The hole within the movable side plate 105 which is penetrated by the mandrel 95 and alignment member 96a during core insertion is so sized that the side plate is engaged by the enlarged shoulder portion 98 of the mandrel 95. Upon such engagement, and with the completion of core expulsion, the movable side plate 105 is forced against the package P to apply a compressive force thereto longitudinally of the replacement core (FIG. 5).

In order to assure proper stripping of the expelled winding core W from the alignment member 96a, and thus prepare the package P for further advance along the common path of travel from the core replacing station, this invention provides a plurality of core gripping spring fingers 115 mounted on the stationary side plate 100. The fingers 115 are spread apart by a winding core W upon expulsion thereof, to grip that core with radially inward force. Upon subsequent withdrawal of the mandrel 95 from the package P, the expelled winding core W is prevented from movement back into the package P by the fingers, and subsequently falls to a discharge chute when pushed from the fingers 115 by the next following core. As the core W is expelled from the package, the replacement core R is released to expand to its normal free length, thus exposing a predetermined short length of the replacement core beyond the leading end of the mandrel 95 (FIG. 5). On commencement of withdrawal of the mandrel 95, the movable side plate 105 returns to its normal position (to the left in FIGS. 3-6), and the package P is drawn against that side plate by the mandrel. Upon the package P being supported by the side plate 105, the mandrel 95 is pulled from within the package P and the exposed end portion of the replacement core R is engaged by the yarn of the package to strip the replacement core R from within the mandrel as it is withdrawn (FIG. 6). Due to the correlation between the free length of the replacement core R and the distance between the internal abutment member 103 and the leading end of the mandrel 95, the engagement of the yarn with the exposed end portion of the expanded replacement core R assures that the replacement core is centered relative to the yarn of the package P, when the mandrel 95 is entirely withdrawn. Upon completion of withdrawal of the mandrel 95 from the package P, the force of the centering springs 101 and 112, if provided in the sidewalls of the apparatus at the core replacing station, returns the package P to a centered position in the pocket of the rotatable member 60. Thereafter, the package P is advanced to the lower chute 51 by further rotation of the rotatable member 60.

In the immediately preceding discussion of the manner in which a replacement core R is shielded within the mandrel 95 during insertion of the core into a package, and is stripped therefrom on withdrawal of the mandrel from the package, it is apparent that the tendency of a wound package of yarn to exert a radially inward force on a supporting core both contributes to the problems of inserting a longitudinally compressible core and contributes to operation of the present subject improvement. Packages exerting such a gripping force, herein referred to as radially compressive packages, may vary in types and in characteristics due to the elasticity of the yarn in the package, the tension applied to the yarn during winding, the pattern of winding of the yarn and still other factors. In any event, the present invention contemplates that the means for locating the replacement core within the hollow mandrel, such as the abutment member 103, accommodates the length of the exposed end portion of the replacement core to the characteristics of the package in such a manner as to assure centering of the replacement core within the package. That is, the exposed length of the re-

placement core is correlated to the force with which the core is gripped by the package upon commencement of withdrawal of the mandrel from the package and to the snugness with which the core is retained within the mandrel. While this exposure may vary, an exposure of one-half to one inch has been found satisfactory in an operating embodiment of this improvement and this range should serve as at least a starting point for any necessary experimentation.

Yet another relationship between the radially compressive packages and the mandrel 95 involves the relative external diameters of the mandrel and the core being replaced. Within the practical limits of force required to cause penetration of the mandrel into a package and possible damage to yarn in the package, it is contemplated that the external diameter of the mandrel may be greater than that of the core. Preferably, in order to minimize the possibility of yarn damage, the mandrel external diameter is no greater than that of the core but is substantially the same.

While particular relationships exist between radially compressive packages and the apparatus of the present invention, as discussed above, it is additionally contemplated that the apparatus of this invention be capable of replacing the core of a package in which the yarn is wound under such tensions as to substantially avoid radially compressive force in the finished package. Such packages are referred to herein as non-compressive packages, in contrast to the radially compressive packages discussed above. If anything, it is even more important that a replacement core be positioned in a predetermined relation to a non-compressive package and maintained in that relation on commencement of withdrawal of the leading end of the mandrel through the package, than is the case in replacing the core of a non-compressive package with a longitudinally compressible core R as discussed above, although relative movement between a package and a replacement core must be avoided in both instances. While the gripping of the replacement core R by the yarn of a compressive package may be employed to at least a limited extent in order to assure that there is substantially no relative movement between replacement core R and the package upon commencement of withdrawal of the mandrel, it is preferred that additional means be provided in order to assure that the replacement core R is always properly stripped from within the protective shield provided by the mandrel 95.

In order to assure that removal of the replacement core R from within the mandrel 95 proceeds in the desired manner, this invention further includes means for temporarily blocking withdrawal of the replacement core R from within the package upon commencement of withdrawal of the leading end of the mandrel 95. In the illustrated embodiment, this means takes the form of an annular member of resilient material having radially inwardly directed portions and referred to herein as a flower 104. The flower 104, which may be fabricated from a thin sheet of plastic material having a natural flexibility and resilience, preferably includes at least a pair of opposed radially inwardly directed petal portions, 104a and 104b. The mandrel 95 includes a pair of openings therein adjacent the spacing member 103 which supports the concealed end of the replacement core R for receiving the petal members 104a and 104b therewithin. As best illustrated by the sequence of use in the FIGS. 3 to 6, the petal portions of the flower 104 are bent forwardly toward the package P upon insertion of the mandrel 95, until such time that the mandrel 95 has penetrated fully through the package P. At that position (FIG. 5), the petal portions 104a and 104b of the flower snap into the openings provided by the mandrel 95. Inasmuch as the flower 104 is mounted upon and movable with the side plate 105, the effect of the petal portions 104a and 104b snapping into the openings provided in the mandrel 95 is to provide a temporary abutment means for the concealed end

of the replacement core R, preventing withdrawal of that end of the replacement core R relative to the side plate 105. Thus, upon commencement of withdrawal of the mandrel 95, the petal portions 104a and 104b engage the end of the replacement core R and maintain the replacement core R in its predetermined position relative to the side plate 105 and to the package P. Thereafter, as withdrawal of the mandrel 95 continues, the petal portions 104a and 104b of the flower are withdrawn from the openings in the mandrel 95, having served their function during the commencement withdrawal of the mandrel. Due to the flexibility and resilience of the material chosen for forming the flower 104, the petal portions 104a and 104b may make the necessary turns to accommodate the insertion and withdrawal of the mandrel 95 (as shown by a comparison of FIGS. 3 and 6).

In order to assure a continuing supply of replacement cores R for the operation of the apparatus, the illustrated apparatus provides means for receiving and storing a plurality of the replacement cores. A replacement core trough 120 adjacent the core replacement station is sized to receive a plurality of such cores R in a predetermined common orientation, and to feed such replacement cores R to a dispensing position in alignment with the mandrel 95 when the same is in the withdrawn position (FIGS. 1 and 2). In order to assure that the next succeeding replacement core is not engaged by the rearward extremity of the mandrel 95 as the mandrel is retracted from the core replacement station, gate control means are preferably provided and controlled in coordination to the sequential operation of the other instrumentalities of the apparatus substantially as shown and described in detail in the aforementioned copending application.

SEMI-AUTOMATIC APPARATUS

It is further contemplated by the present invention that a longitudinally compressible replacement core may be substituted for a supporting core in a package of yarn through the use of an apparatus which is not sequentially actuated as described immediately above. More particularly, insertion of longitudinally compressible replacement cores as contemplated by this invention may be accomplished by an apparatus comprising an elongate hollow mandrel and an alignment member substantially similar to those discussed above, package supporting means for receiving and supporting a package against forces arising during penetration of the package by the mandrel, and means for causing relative movement between the mandrel and sleeve and a package supported on the package supporting means so that a winding core is pushed from the package as a replacement core is inserted thereinto. Such an apparatus, as illustrated in FIG. 8, may employ a double-acting pressure fluid cylinder 200 having a mandrel member 210 mounted on the piston rod 201 thereof and positioned relative to a package supporting table 220 so that, upon application of pressure fluid to the cylinder 200 under the control of an appropriate valve 202, the mandrel member 210 is moved relative to the package supporting table 220 and penetrates a package P' supported on the table 220. In similarity to the sequentially actuated apparatus discussed above, means are provided for engaging a winding core W' and a replacement core R' at least partially enclosed by the mandrel 210 to push the winding core W' from the package and the replacement core R' into the package as the mandrel is displaced from a position remote from the package to a position penetrating the package and the mandrel shields the replacement core R' from engagement by the package during insertion of the replacement core thereinto. The mandrel 210 is formed with dimensions related to those of the package and cores in the manner described above with reference to the mandrel 95 and an alignment member 211 is supported therewith for facilitating penetration of the mandrel into a package. An abutment member 214 for

engaging a trailing end of a replacement core received between the alignment member and the mandrel is disposed within the annular volume defined therebetween. The correlation between the length of the annular volume adapted to receive a replacement core R' and the free length of the replacement core is substantially the same as described above, and the mandrel performs in a substantially identical manner.

In order to provide for longitudinal compression of a package during the insertion of a replacement core R' and to provide for stripping of the replacement core R' from within the mandrel 210, a stripper plate 215 is supported in spaced relation to the package supporting table 220, for engagement by the mandrel 210. Preferably, the plate 215 is supported by a plurality of rods 216 and is biased into a position raised above the height of a package P' by a plurality of compression springs 218. Mounted upon the upper surface of the stripper plate 215 is a flower 219, similar to the flower 104 discussed above with reference to the sequentially operated apparatus. The mandrel 210 is provided with openings for receiving the petal portions 219a and 219b of the flower (FIGS. 9 and 14).

In the use of a mandrel as described immediately above, it has been noted that winding cores may be expelled from packages, and replacement cores inserted thereinto, even though the mandrel is employed in a hand operation and reliance is not placed upon the use of a fluid pressure cylinder such as cylinder 200 to provide the relative movement between the mandrel and a package. When such a hand operation is used, it has further been found that it is not necessary to provide a package supporting means such as the table 220 against which the package is compressed during the expulsion and insertion of a replacement core.

In the drawings and specification there have been set forth preferred embodiments of the invention and, although specific terms are employed, they are used in a generic and descriptive sense only and not for purposes of limitation, the scope of the invention being defined in the claims.

I claim:

1. In an apparatus for replacing the core of a radially compressive, core-supported wound yarn package which includes means for supporting such a package against forces arising during insertion of a replacement core thereinto, and core replacing means operatively associated with said supporting means for engaging a package supported thereby, for expelling a supporting core therefrom, and for inserting a longitudinally compressible replacement core thereinto, the improvement comprising: an elongate hollow mandrel adapted to penetrate entirely through a package and having an effective external diameter substantially equal to that of a package supporting core which is to be replaced and an effective internal diameter greater than the external diameter of a replacement core to be inserted, the leading end of said mandrel being open and being adapted to penetrate through a package, and means operatively associated with said hollow mandrel for locating a replacement core therewithin one end of such core exposed outside said leading end of said mandrel and the package upon penetration of said leading end entirely through the package, so that the replacement core is positioned in a predetermined relation to the package and maintained in that relation upon commencement of withdrawal of said leading end through the package.

2. The combination of claim 1 wherein said mandrel is a tubular, thin wall, right-circular cylindrical member.

3. The combination of claim 2 wherein said leading end lies in a plane substantially perpendicular to the longitudinal axis of said mandrel.

4. The combination of claim 1 and further comprising an elongate alignment member supported within said man-

drel and substantially coaxially therewith and extending outwardly thereof beyond said leading end of said mandrel for entering into a package supporting core and assuring proper engagement between such core and said mandrel.

5. The combination of claim 4 wherein said alignment member is a right-circular cylindrical member having an external diameter which is no greater than the smaller of the internal diameters of said package and replacement cores.

6. The combination of claim 1 wherein said means for locating a replacement core within said mandrel comprises an abutment member supported within said mandrel for engagement by a replacement core received therewithin and spaced from said leading end a distance less than the normal free length of a replacement core so as to determine the length of said end portion of a replacement core exposed for gripping engagement by a package.

7. Means for replacing the core of a radially compressive, core-supported wound yarn package and for inserting a longitudinally compressible replacement core thereinto comprising:

an elongate hollow mandrel adapted to penetrate entirely through a package and having an external diameter substantially equal to that of a package supporting core which is to be replaced and an internal diameter greater than the external diameter of a replacement core to be inserted, the leading end of said mandrel being open and being adapted to penetrate through a package, and

means operatively associated with said hollow mandrel for locating a replacement core therewithin with one end of such core exposed outside said leading end of said mandrel and the package upon penetration of said leading end entirely through the package, so that the replacement core is positioned in a predetermined relation to the package and maintained in that relation upon commencement of withdrawal of said leading end through the package.

8. A means according to claim 7 wherein said mandrel is a thin wall, right-circular cylindrical tubular member.

9. A means according to claim 8 wherein said leading end lies in a plane substantially perpendicular to the longitudinal axis of said mandrel.

5 10. A means according to claim 9 and further comprising an elongate alignment member supported within said mandrel and substantially coaxially therewith and extending outwardly thereof beyond said leading end of said mandrel for entering into a package supporting core and assuring proper engagement between such core and said mandrel.

10 11. A means according to claim 10 wherein said alignment member is a right-circular cylindrical member having an external diameter which is no greater than the smaller of the internal diameters of said package and replacement cores.

15 12. A means according to claim 11 wherein said means for locating a replacement core within said mandrel comprises an abutment member supported within said mandrel for engagement by a replacement core received therewithin and spaced from said leading end a distance less than the normal free length of a replacement core so as to determine the length of said end portion of a replacement core exposed for gripping engagement by a package.
